DEFENSE WEAPON

Jacob Osses, Roxbury Crossing Station, Mass.

Application December 12, 1945, Serial No. 634,595.

5 Claims. (Cl. 222—389)

1

My invention relates to improvements in defense weapons of the fluid ejecting type.

The primary object of the invention is to provide a light weight, pocket type, weapon of inexpensive construction and few parts which is handy to carry in a pocket and designed for quick action to expel, for a considerable distance, a liquid for defense purposes and also for marking an assailant, or thief, for subsequent identification as such.

Other and subordinate objects, also, comprehended by my invention, together with the precise nature of my improvements, and the manifold advantages of the same, will become readily apparent when the succeeding description and claims are read with reference to the drawings accompanying and forming part of this specification.

In said drawings:

Figure 1 is a view in longitudinal section of my improved defense weapon, in a preferred embodiment thereof, with the parts shown in position for firing the weapon.

Figure 2 is a fragmentary similar view drawn to an enlarged scale.

Figure 3 is a view in transverse section taken on the line 3—3 of Figure 2.

Figure 4 is a similar view taken on the line 4—4 of Figure 2.

Figure 5 is a view similar to Figure 1 drawn to an enlarged scale with the parts shown in the positions assumed thereby after the weapon has been fired.

Figure 6 is a view in transverse section taken on the line 6—6 of Figure 5.

Figure 7 is a view similar to Figure 1 of a modified embodiment of my improved weapon.

Figure 8 is a view in transverse section taken on the line 8—8 of Figure 7.

Figure 9 is a similar view taken on the line 9—9 of Figure 7, and

Figure 10 is another similar view taken on the line 10—10 of Figure 7.

Describing my invention in detail, with reference to the drawings by numerals, and referring first to Figures 1 to 6, my improved defense weapon as shown comprises a substantially cylindrical barrel 1 of any suitable length and diameter having a front end closure cap 2 threaded thereon as at 3, and formed with a tapering front end 4 having an axial threaded bore 5 therein substantially smaller than the internal diameter of the cylinder 1. The bore 5 has threaded therein a reduced shank 6 of a nozzle member 7 provided with an axial bore 8 extend-

2

ing through the shank 6 and having an enlarged front end 9 adapted to be packed with a soft wax plug 10 for preventing leakage of liquid out of the barrel 1 at the front end thereof while the weapon is being carried in a pocket, or the like, the plug 10 being designed for ejection out of the nozzle member 7 when the weapon is fired, in a manner presently described. A suitable gasket 11 is interposed between the closure cap 4 and the front end of the cylinder 1, and another such gasket 12 between the nozzle member 7 and said closure cap 4. The inner end of the shank 6 of the nozzle member 7 is suitably cross grooved and recessed, as represented at 13, to obviate clogging of the bore 8, at the inner end thereof, by solids in the liquid to be contained in the barrel 1 for ejection out of said bore and nozzle member 7. A second closure cap 14 is threaded, as at 15, part way onto the rear end of the barrel 1. The closure cap 14 is provided with an intermediate, circumferential, internal shoulder, as at 16, adapted to abut the rear end of the barrel 1 and thereby space the rear end of said cap 14 from said rear end of the barrel to provide a reduced chamber 17 in said cap at the rear end of said barrel. An axial bore 18 is provided in the rear end of said cap 14 for a purpose presently seen.

A hollow cylindrical plunger 19 is fitted in the barrel 1 for endwise sliding movement therein. The front end 20 of the plunger 19 is closed with the exception of an axial through bore 21 therein for a blowout plug 22 serving a purpose presently clear. The plunger 19 is designed to pass gas therethrough and for that purpose is provided adjacent to its front end with a pair of diametrically opposite discharge ports 23 therein. Suitable soft metal sealing rings 24 and grease packing rings 25 are countersunk in the front portion 40 of the plunger 19, also a grease packing ring 26 in the rear end of said plunger 19. Longitudinal, internal, gas conducting grooves 27 extend from the rear end of the plunger 19 to the ports 23. Under conditions, presently described, the ports 23 are designed to register with an internal annular gas escape groove 28 in the front end portion of the barrel 1 and which opens into longitudinally extending gas escape grooves 29 in said end portion leading to the front end of said barrel. The front end 20 of the plunger 19 is suitably recessed in its front face, as at 30 to provide for the escape of gas out of the grooves 29 to the bore 8 of the nozzle member 7. The reason for providing the recesses 30 will be presently rendered clear. The plunger 19 is de-

signed to be releasably retained in a retracted position in the rear end portion of the barrel 1 and by means of a split resilient ring 31 accommodated in the circumferential groove 32 in the rear end portion of said plunger and normally expanded into an internal circumferential groove 33 in the rear end portion of the barrel 1. The groove 33 tapers transversely toward the front end of the barrel 1 to cam said ring into the groove 32 upon slight movement of the plunger 19 forwardly and thereby release said plunger.

Suitably fixed in the rear end of the chamber 17 is an annular percussion detonator 34 which may be of any suitable type adapted under percussion to ignite a fuse 35 and explode a substance 36 therein generating gas when exploded. The detonator 34, while fixed in the chamber 17, is adapted to be replaced as will be clear.

A percussion sleeve 37 is provided for exploding the detonator 34 and which is adapted to slidably fit in the rear end portion of the plunger 19 for projection rearwardly out of said plunger against the detonator 34 by means of a coil spring 38 interposed in the plunger 19 between the percussion sleeve and the front end 20 of said plunger.

Means are provided for releasably retaining the percussion sleeve 37 in a forwardly retracted, cocked position in the rear end of the plunger 19, when said plunger is retracted, and whereby the coil spring 38 is compressed to tension said sleeve for projection and release. The aforesaid means comprises a tubular detent member 39 having a rear end suitably fixed in the bore 18 of the cap 14, and which extends forwardly in said cap 14 through the detonator 34 and is adapted to extend into the rear end of the plunger 19 with its front end extended part way into the percussion sleeve 37. The percussion sleeve 37 is provided with an enlarged bore portion 40 forming an internal shoulder 41 in the sleeve and the detent 39 is longitudinally split, as at 42, forwardly of the detonator 34 to be expanded at its front end into the bore portion 40 so as to engage the shoulder 41 and thereby prevent the percussion sleeve 37 from being projected. As will be understood, the detent 39 is formed of resilient material so that it will react out of expanded position throughout the split portion thereof. A rod-like expander member 43 with an enlarged front end head 44 is slidably mounted in the rear end of the detent member 39 for endwise movement in said member 39 forwardly and rearwardly, respectively, to move said head out of and into the front end of the detent member. The head 44 is adapted, when moved into said end of the detent member 39, to expand said member in the manner described and for movement out of said end of the detent member 39 to permit said member to contract. At this point, it may be explained, that when the detent member 39 contracts, the front thereof becomes disengaged from the shoulder 41 so that said percussion sleeve 37 is freed to slide rearwardly along said member 39. Preferably, for moving the expander member 43 forwardly and rearwardly, an endwise manipulative resilient bar is provided to extend alongside the barrel 1 and cap 14. The bar 45 is provided with a right angled rear end 46 suitably fitted over a reduced rear end stud 47 on the expander member 43 and retained on said stud by means of a set collar 48 provided on the stud. The bar 45 is adapted to be moved rearwardly to correspondingly move the expander member 43 and enter the head 44 in the front

end of the detent 39 and such movement of said bar and expander member 43 is limited by frictional engagement of said head 44 with the inner surface of said detent 39.

5 In the rearward limit of movement of said bar 45, the front end thereof is adapted to be releasably retained behind the rear end of the closure cap 2 so as to block forward movement of said bar 45 until the same is released. For retaining 10 the front end of said bar 45 behind the rear end of the closure cap 2, a ring assembly is provided 15 comprising a pair of side-by-side rings 49, 50 riveted together as at 51, and suitably fixed on the barrel 1 adjacent to the closure cap 2, and a third ring 52 rotatably mounted in a groove 53 formed by the rings 49, 50, conjointly. The rings 49, 50 are provided with a pair of edge notches 54 which are aligned and through which the front end portion of the bar 45 extends. The ring 52 is provided with an edge notch 55 adapted to be rotated in registration with the notches 54. When the ring 52 is rotated to move the notch 55 out of registration relative to the notches 54, said ring 52 retains the front end portion of the bar 20 25 45 at the bottom of the notches 54 and behind the rear end of the closure cap 4. By rotation of the ring 52 to register the notch 55 with the notches 54, as by the finger of a hand grasping the barrel 1, the front end portion of said rod 30 35 45 will be permitted to flex into the notch 55 and into released position as will be clear. A thumb grip member 56 is provided on the bar 45 in the rear of the described ring assembly and for use in manipulating said bar.

35 Referring now to the use and operation of the described embodiment of my invention. When the plunger 19 is releasably locked, or retained, in its described retracted position, and the percussion sleeve 37 is cocked in the manner already 40 described, the plunger 19 together with the closure cap 2 and the portion of the barrel 1 in front of said plunger, form a closed and sealed chamber 57 for containing a liquid to be discharged by the weapon. In this connection, my invention 45 comprehends the use in the chamber 57 of a suitable liquid, not shown, having a strong odor such as would deter an assailant from coming into close contact with a person using the weapon of my invention, and also adapted to leave a substantially permanent stain on the clothing or flesh of anyone upon whom the liquid may be discharged by the weapon. With the chamber 57 loaded with such a liquid, the weapon is fired as follows. The ring 52 is rotated to release the 50 front end of the bar 45, in the manner already described, the barrel 1 being held in one hand and said ring rotated with manipulation of a finger of the hand. The bar 45 may then be shoved forwardly by means of the thumb piece 56 to 55 move the expander member forwardly so that the head 44 is moved out of the front end of the detent member 39 to permit the detent member to contract so that the percussion sleeve 37 may move rearwardly over said detent member. As 60 soon as the percussion sleeve 37 is thus released, or unlocked, the coil spring 38 acts to reject said sleeve out of the rear end of the plunger 19 and into the detonator 34 to impact the fuse 35 by pressing the same against the rear end of the cap 65 70 75 80 85 90 95 100 105 110 115 120 125 130 135 140 145 150 155 160 165 170 175 180 185 190 195 200 205 210 215 220 225 230 235 240 245 250 liquid out of the chamber 57 by way of the nozzle member 7, the ejecting liquid forcing the plug 10 out of said member. The plunger 19 is limited in its forward movement by engagement of the front face of the front end 20 with the gasket 11, thereby spacing said face from the front end of the closure cap 4. As the plunger 19 reaches its limit of forward movement, the ports 23 register with the gas escape groove 28 and the burnt gas discharges from the barrel 1, and plunger 19 by way of said ports 23, the grooves 28 and 29, the space between the front end 20 of the plunger and the end of the closure cap 4 and out of the bore 8, such gases reaching the described space by way of the recesses 30. The gas conducting grooves 27 provide for the gas entering the plunger 19 around the percussion sleeve 37.

To reload after firing, the end 46 of the bar 45 is detached from the stud 47, after removing the set collar 48, the bar 45 being pulled rearwardly to detach said end thereof. The cap 47 may then be detached from the barrel 1 together with the detent member 39 and the expander member 43, and the percussion sleeve 37 on said detent member. A new detonator 34 may then be positioned in the chamber 17, the percussion sleeve slid along the detent member 39 until the shoulder 41 is in front of the front end of said detent member 39 after which the expander member 43 may be moved rearwardly of the cap 14 to expand said detent member into the enlarged bore portion 40 and behind said shoulder 41. The cap 14 may then be replaced, together with the parts carried thereby, and the rear end 46 of the bar 45 reattached to the stud 47. The ring 53 may then be rotated to retain the front end portion of the bar against the rear end of the closure cap 4 in the manner already described. With the closure cap 4 detached, the plunger 19 may be shoved rearwardly into cocked position, in opposition to the spring 38, and by any suitable instrument. The chamber 57 may then be refilled with liquid and the closure cap 4 replaced. The blowout plug 7 is a safety provision to prevent the weapon from being shattered in case the plunger 19 should freeze to the barrel 1 for any unforeseen reason.

In the modified embodiment of the invention shown in Figures 7 to 10, the plunger 57 is projected forwardly in the barrel 58 by a compression spring 59 fitted in said plunger and interposed between the front end of the same and the rear end of the rear cap 60. The barrel 58 is provided with an enlarged reinforced intermediate portion 61 through which a stud 62 extends into a longitudinal groove 63 in the plunger 57 to prevent the plunger from turning in the barrel 58.

A ring assembly of two side-by-side rings 63, 64 and a third assembly manipulating ring 65 clamped between the rings 63, 64 is slidably mounted on the barrel 58 adjacent to the front closure cap 66 against which said ring assembly is slidable as shown by dotted lines in Figure 7.

The plunger 57 is adapted to be retained in retracted position, in opposition to the spring 59, by means of a pin 67 extended radially through the portion 61 into a radial aperture 68 in the plunger. The pin 67 is suitably secured at one end in the rear end of a plunger releasing arm 69 suitably mounted on a stud 70 to extend alongside the barrel 58 and be rocked about said stud 70 so as to withdraw the pin 67 out of the aperture 68 and thereby release the plunger 57 for projection forwardly in the barrel 58 by the

spring 59. The described ring assembly 63, 64, 65 may be slid rearwardly along the barrel 58 to position the ring 64 under the front end of said lever 69 thus blocking swinging of said lever in a direction to cause release of the plunger 57. The stud 70 is threaded into the portion 61 and extended through the lever 69 so that the rear end portion of said lever abuts the portion 61 when the pin 67 is entered in the aperture 68 and said lever is thereby prevented from being swung away from the barrel 58 into a position such that the entire ring assembly 63, 64, 65 may be moved under said lever. A ring assembly latching leaf spring 71 is fixed at one end thereof, by screws 72, to the portion 61 to extend alongside the barrel 58 forwardly of said portion. The leaf spring 71 is provided with a hooked front end 73 adapted to snap into an internal groove 74 in the ring 64 when the ring assembly 63, 64, 65 is moved into a position such that the ring 64 is under the front end of the lever 69.

In operating the described modified embodiment of my invention, the leaf spring is first flexed toward the barrel 58 to release the ring assembly 63, 64, 65 in a manner which will be clear. Said assembly is then shoved forwardly to displace the ring 64 from under the front end of said lever 69 and thereby free said lever for operation. The lever 69 is then swung toward the barrel 58, on the stud 70, withdrawing the pin 67 from the aperture 68 and thus releasing the plunger 57 for operation by the spring 59. The modified embodiment of the invention is designed to be used in the same manner as the first described embodiment and to eject the same kind of liquid, not shown.

The foregoing, it is believed, will suffice to impart a clear understanding of my invention without further explanation.

Manifestly, the invention, as described, is susceptible of modification without departing from the inventive concept, and right is herein reserved to modifications as fall within the scope of the appended claims.

What I claim is:

1. In a weapon for ejecting liquid, a barrel, a front end nozzle in the barrel, a plunger in said barrel adapted to be slid rearwardly therein into a retracted position to provide a liquid containing chamber in the barrel in front of said plunger, means to project said plunger forwardly comprising a percussion detonator cap in said barrel in the rear of said plunger, said detonator cap adapted to be ignited by impact, and means for impacting said cap movably out of said plunger rearwardly in said barrel.

2. In a weapon for ejecting liquid, a barrel, a front end nozzle in the barrel, a plunger in said barrel adapted to be slid rearwardly therein into a retracted position to provide a liquid containing chamber in the barrel in front of said plunger, means to project said plunger forwardly comprising a percussion detonator cap in said barrel in the rear of said plunger, said detonator cap adapted to be ignited by impact, and means for impacting said cap comprising a spring tensioned percussion sleeve slidable in said plunger, and detent devices for releasably holding said sleeve stationary in opposition to said spring.

3. In a weapon for ejecting liquid, a barrel, a front end nozzle in the barrel, a plunger in said barrel adapted to be slid rearwardly therein into a retracted position to provide a liquid containing chamber in the barrel in front of said plunger, means to project said plunger forwardly comprising

ing a percussion detonator cap in said barrel in the rear of said plunger, said detonator cap adapted to be ignited by impact, and means for impacting said cap comprising a spring tensioned percussion sleeve slidable in said plunger, an expansible detent member for holding said sleeve stationary in opposition to said spring, an expander member for said detent member movable into and from expanding position in said detent member, and manipulative means for moving the expander member.

4. In a weapon for ejecting liquid, a barrel, a front end nozzle in the barrel, a plunger in said barrel adapted to be slid rearwardly therein into a retracted position to provide a liquid containing chamber in the barrel in front of said plunger, means to project said plunger forwardly comprising a percussion detonator cap in said barrel in the rear of said plunger, said detonator cap adapted to be ignited by impact, and means for impacting said cap comprising a spring tensioned percussion sleeve slidable in said plunger, an expansible detent member for holding said sleeve stationary in opposition to said spring, an expander member for said detent member movable into and from expanding position in said detent member, and manipulative means for moving the expander member comprising a bar extending alongside said barrel and connected to said expander, said bar being endwise movable in one direction to move the expander member from expanding position.

5. In a weapon for ejecting liquid, a barrel, a front end nozzle in the barrel, a plunger in said barrel adapted to be slid rearwardly therein into a retracted position to provide a liquid containing chamber in the barrel in front of said plunger, means to project said plunger forwardly comprising

ing a percussion detonator cap in said barrel in the rear of said plunger, said detonator cap adapted to be ignited by impact, and means for impacting said cap comprising a spring tensioned percussion sleeve slidable in said plunger, an expansible detent member for holding said sleeve stationary in opposition to said spring, an expander member for said detent member movable into and from expanding position in said detent member, manipulative means for moving the expander member comprising a bar extending alongside said barrel and connected to said expander, said bar being endwise movable in one direction to move the expander member from expanding position, and means to restrain said bar against such movement.

JACOB OSSES.
